UNITED STATES PATENT OFFICE.

WILLIAM BAYLEY, OF SPRINGFIELD, OHIO.

SWINGING WINDOW-SASH.

1,115,160.

Specification of Letters Patent. Patented Oct. 27, 1914.

Application filed December 22, 1913. Serial No. 308,071.

To all whom it may concern:

Be it known that I, WILLIAM BAYLEY, a citizen of the United States, residing at Springfield, in the county of Clark and State of Ohio, have invented certain new and useful Improvements in Swinging Window-Sashes, of which the following is a specification.

My invention relates to swinging window sashes and particularly to means for pivotally supporting such sashes at points intermediate their extremities.

Window sashes for use in factories, auditoriums or public buildings are frequently constructed in units of great length, in some cases approximating several hundreds of feet. Such sashes as commonly constructed, are too heavy to be supported upon trunnions located only at the extreme ends.

20 The present invention is designed to afford means for pivotally supporting such a window sash at various points throughout its length, whereby it may be swung about such pivotal connection as a single unit.

25 The object of the invention is to simplify the structure as well as the means and mode of operation of such swinging sashes, whereby they will not only be cheapened in construction, but will be more efficient in 30 use, capable of being easily and quickly operated and unlikely to get out of alignment or repair.

Referring to the drawings, Figure 1 is a vertical sectional view of a metallic window sash, showing the medial support therefor, which forms the subject matter hereof. Fig. 2 is a front elevation of a window sash, showing one of the end trunnions and one of the medial supports. Fig. 3 is an enlarged detail vertical sectional view of the 40 medial pivotal connection. Fig. 4 is a similar sectional view upon line $\alpha-\alpha$ of Fig. 3. Fig. 5 is a transverse sectional plan view of the connection. Fig. 6 is a detail perspective view of the bearing block. Figs. 45 7 and 8 are detail side elevation and front elevation respectively of a modification of the construction shown in the preceding figures. Fig. 9 is a detail view showing the 50 use of the channel iron in lieu of the I beam shown in the preceding figures. Figs. 10, 11, 12 and 13 illustrate further modifications of the construction shown in the previous figures.

Like parts are indicated by similar characters of reference throughout the several views.

In the drawings, 1 is the cap bar and 2 the sill bar of the window opening. In this case both cap and sill bars are shown as 55 angle irons. While the swinging sash may be of any suitable construction, it has been shown in the drawings as a metallic sash and having transversely arranged sash bars 3 upon which are supported the glass 4. 60 The margins of the sash are provided with angle irons 5, which abut upon the cap and sill bars 1 and 2 and upon the vertical frame bars 6 at the sides of the window opening when the sash is in its closed position. The 65 sash is connected with the vertical frame bars 6 at each side of the window opening by trunnions 7 of any suitable construction. As thus far described, the construction does not differ from that commonly employed in 70 swinging metallic window sashes.

Located at intervals throughout the window opening are vertical struts or posts 8 connected by brackets 10 with the cap and sill bars 1 and 2. Each of the vertical struts 80 8 is offset as at 9 at a point in alignment with the axis of oscillation of the shaft. The construction is such that the upper portion of each strut will be upon one side of the sash, and the lower portion thereof 85 will be located upon the opposite side of the sash, while the transverse connecting or offset portion 9 extends through the sash. To permit the strut or post 8 to pass through 90 the sash without interfering with the swinging movement thereof, the vertical sash bars 3 are arranged in pairs one upon each side of each strut or post as is shown in Fig. 2. It will be understood that the vertical sash bars 3 are so arranged only at points coincident with struts or supports and that intermediate the supports or struts, single sash bars are employed in the usual manner. In Figs. 1 to 5 of the drawings, the supports or struts 8 have been shown in the form of 95 I beams. It is obvious that rectangular bars may be employed or that channel irons as shown in Fig. 9 may be substituted for the I beams.

The vertical sash bars 3 are spaced apart 105 a distance only sufficient to permit the strut or support to pass between them. The strut or support is provided with a hole or open-

ing in axial alinement with the trunnion 7 at ends of the sash. As shown in the drawing, such pivotal opening is located in the transverse or offset portion of the strut.

5 Located in the channel of the I beam on opposite sides of the support or strut, are filler blocks 10 extending flush with the opposite faces of the beam. The filler blocks are secured in place by riveting as indicated 10 at 11. Each filler block is provided with a hole registering with that of the strut or support. Secured to the parallel sash bars 3 and located intermediate the webs thereof, is a recessed bearing block 13 through which 15 the transverse portion of the strut with the attached filler blocks 10 projects. The bearing block 13 is likewise provided with an opening 14, registering with the corresponding openings of the filler blocks and strut.

20 A trunnion or stud 15 passes through the registered openings of the bearing block, the filler blocks and the strut as shown in Fig. 4. The bearing blocks 13 being secured to the parallel sash bars by means of rivets or 25 by bolts as shown in Fig. 4, will oscillate in unison with the sash about its pivotal connection with the strut or support formed by the trunnion stud 15. It is to be understood that this trunnion stud 15 is an axial alinement with the trunnions 7 at the opposite ends of the sash.

In assembling the structure, the filler blocks 10 are placed in position on opposite sides of the strut to fill the channels thereof. 30 The bearing block 13 is then passed over the end of the strut which passes through the recess of the block until the opening 14 is brought into registry with the corresponding opening of the filler block and struts, whereupon the trunnion stud 15 is inserted. The trunnion stud 15 is of such length as to 35 extend substantially flush with the faces of the bearing block 13. The sash is then placed in position and secured to the bearing block by means of rivets or by the bolts as indicated in Fig. 4. It will be noted that the webs of the parallel sash bars 3 extending on opposite sides of the bearing block 13, prevent the escape of the trunnion stud 40 15. The sash will then be free to swing upon the trunnions 7 at its extremities and the medial trunnion studs 15, which are distributed at intervals throughout its length. The narrow slot or opening in the sash intermediate the parallel sash bars 3, above 45 and below the offset of the strut or post are closed by narrow strips 16 of metal, glass or other material secured therein by cement or other means in a manner similar to the manner of securing the glass 4. In the event that a channel beam is employed in lieu of the I beam previously described, a single 50 filler block 12 will be employed as shown in Fig. 9. Otherwise, the construction is the 55 same as previously described.

In Figs. 7 and 8 there is shown a modification of the construction in which there is employed a strut or post formed from angle irons 17 arranged in pairs, each member of the pair being in reversed position and the pairs being offset one with the other, whereby one pair of angle irons will be on one side of the sash and the other pair upon the opposite side of the sash, the adjacent ends of the two pairs of the angle irons being connected by a coupling plate 18, which is interposed between the individual angle irons of each pair. In this case the vertical frame sash bars 3-3 will be separated one from the other a distance equal to the thickness of 60 the coupling plate 18.

The construction and operation of the sash is similar to that previously described. Any suitable means may be provided for adjusting the sash or maintaining it in its adjusted position.

In Fig. 10 there is shown a modification somewhat similar to that disclosed in Figs. 7 and 8 but differing therefrom in that the uprights or struts 19 may be single members, 65 either bars, channels or I beams and are connected by a transverse horizontally disposed plate 20 in lieu of the vertical plate 18 in the previous construction. In this construction the sash is provided with two parallel centrally disposed sash bars 3-3 arranged one upon each side of the axis of oscillation. This provides an intermediate space 21 through which the transverse connecting plate 20 projects. The opening 100 above and below the plate 20 is closed by flexible flanges 22 secured to the sash bars 3 upon each side of the plate and bearing at their free edges upon the plate 20. These flanges 22 are adapted to yield as the sash is 105 oscillated and by their resiliency maintain a constant engagement with the transverse connecting plate 20.

In Fig. 11 there is shown a modification employing a straight upright or strut 23 and an offset sash, the sections 24 of which are connected by a transverse horizontally disposed plate 25. The plate 25 is provided with suitable perforations or openings 110 through which the upright or strut 23 projects. In this construction one section 24 of the sash is located at the inner side of the upright or strut 23, while the other section is located at the outer side of the strut. This construction permits the sash to be oscillated as indicated by dotted lines without 115 interfering with the strut or support.

The particular form of swinging sash and supporting strut herein shown and described lends itself readily to the application of fly 120 screens. It has heretofore been the custom when applying fly screens to swinging sashes to form the screen into a semi cylindrical form or chamber within which the swinging sash may oscillate. By the present construc- 125 130

tion the screen may be adjusted parallel with the normal position of the sash and permanently secured in position. Thus the fly screen will occupy no more space and will not differ in appearance from the screen constructed as ordinarily employed with sliding windows.

In Fig. 10 screen sections 26-26 are shown supported upon the strut sections 19, 10 where they are secured by angle bars or other means as indicated at 27. It is to be noted that the screen is divided into two sections one section being located upon the outer side of the sash and the other section 15 upon the inner side of the sash. By this construction the sash in its oscillatory movement will move to and from the respective sections. The space intermediate the adjacent edges of the screen sections is effectually closed by the spring flanges 22. The 20 application of screen sections to the construction shown in Fig. 11 is quite similar to that of Fig. 10. The screen sections 26 are secured to the opposite sides of the upper right or strut 23.

In Fig. 11, yielding spring flanges 28 are shown supported upon the upright or struts 23 and bearing at their free edges upon the transverse connecting plate 25 by which the 30 sash sections 24 are connected one with the other. These spring flanges by maintaining their contact with the plate 25 at all times close the opening between the respective sections of the sash and the screen.

In Figs. 12 and 13 there is shown constructions quite similar to that disclosed in Figs. 1 to 5. Two different methods of applying screens to such constructions are shown in these figures. In Fig. 12, screen sections 29 are stationarily secured to the opposite sides of the offset studs or supports. These screen sections 29 each have a flexible section 30 at their adjacent edges, which section is secured to the swinging sash. As the sash is oscillated about its pivotal connection, the flexible section 30 will yield as indicated by dotted lines to permit the ready movement of the sash while effectually closing the window opening against the entrance of insects. It will be noted in this figure that one portion of the screen section is secured to the strut or support while the other portion is secured to the sash.

In Fig. 13 is shown a construction somewhat similar in which the screen sections 31 are secured at their outer or extreme edges to the strut or support or if desired may be secured direct to the window casing, while at their inner or adjacent edges the screen sections 31 are attached to opposite sides of the swinging sash. The screen sections 31 being flexible permit the ready adjustment of the sash the screen sections assuming positions as indicated by dotted lines in said figure.

From the above description it will be apparent that there is provided a device of the character described, possessing the particular features of advantage before enumerated as desirable, but which is obviously susceptible of modification in its form, proportion, detail construction or arrangement of parts, without departing from the principle involved or sacrificing any of its advantages.

While in order to comply with the statute, 75 the invention has been described in language more or less specific as to certain structural features, it is to be understood that the invention is not limited to any specific details, but that the means and construction 80 herein described comprise but one mode of putting the invention into effect, and the invention is therefore claimed broadly in any of its possible forms or modifications 85 within the scope of the appended claims.

Having thus described my invention, I claim:

1. A swinging sash, supporting struts therefor extending through the sash at points coincident with the axis of oscillation, and pivotal connections between the sash and the struts.

2. A swinging sash having openings therein coincident with the axis of oscillation, supports therefor projecting through 95 said openings and pivotal trunnions connecting the sash and supports.

3. A window sash swinging on a medial axis of oscillation and a plurality of separated pivotal trunnions therefor arranged 100 in spaced relation intermediate the ends of the sash and coincident with the axis of oscillation, and a strut extending through the sash and supporting the said trunnions.

4. A swinging sash having medially disposed trunnions at its opposite ends, a strut 105 passing through the sash intermediate its ends and an intermediate trunnion carried by the strut, separated from, but alined with the end trunnions.

5. In a window construction as described, means for supporting a swinging sash intermediate its ends comprising a plurality of offset struts having their transverse connections projected through the sash and pivotal connections between such transverse 115 portions of the struts and the sash.

6. A window sash having transverse sash bars arranged in pairs, the bars of each pair being separated one from the other, a supporting strut projecting through the intermediate space between the sash bars and a pivotal connection between the sash bars and strut.

7. A swinging window sash, a supporting strut located intermediate the ends of the sash, said strut connected with the sill of the window space at one side of the sash and with the window cap at the opposite 125 side of the sash, said strut being projected 130

through the sash intermediate its ends, and a pivotal connection between the sash and strut.

8. A swinging sash having parallel spaced sash bars, a bearing block interposed between adjacent sash bars and a support to which the bearing block is pivotally connected.

9. A swinging sash, an offset strut and a recessed bearing block through which the strut projects and pivotally connected therewith, the bearing block being connected with the sash at a point intermediate the extremities thereof.

10. A swinging sash having parallel sash bars, a recessed bearing block having a transverse opening therein, a supporting strut projecting within the recess of the bearing block and having a transverse opening registering with that of the bearing block, a pivotal trunnion extending through the registering transverse openings of the bearing block and strut to pivotally connect said parts one with the other, said bearing block being secured between parallel sash bars whereby the said sash bars will close the opposite extremities of the bearing block opening to prevent the escape of the trunnion.

11. A swinging sash, a supporting strut for the sash located intermediate the ends

thereof, intersecting the plane of the sash and pivotal connections between the strut and sash.

12. A swinging sash, a strut extending through the sash and thence parallel with the normal position of the sash but on opposite sides thereof, and a pivotal connection between the strut and sash.

13. A swinging sash comprising a plurality of units arranged side by side, a plurality of supporting heads located intermediate the sash sections, oppositely disposed arms carried by the heads, said arms being interposed between the adjacent sides of succeeding units, and a supporting frame with which the arms are connected.

14. A swinging window sash, a supporting member located in the plane of the sash and coincident with its axis of oscillation, and supports for the said member located at points intermediate the extremities of the sash.

In testimony whereof, I have hereunto set my hand this 4th day of December, 1913.

WILLIAM BAYLEY.
